UNITED STATES PATENT OFFICE

JOSEPH MUROS, OF NEW YORK, N. Y.

SAFETY RAZOR

Application filed March 22, 1928. Serial No. 263,666.

The present invention relates to improvements in safety razors, and more particularly to that type in which a blade holder is oscillatably mounted upon a frame, the cutting edge of a blade co-operating with a guard, which is movable and provided with lugs adapted to be engaged by said cutting edge, the arrangement being such that the said lugs are capable of being disengaged from the blade to permit the latter to be swung into a position in which it may be stropped.

The main object of the invention is to generally simplify the construction above referred to and thereby not only to make it less expensive to manufacture, but also considerably lighter in weight.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

A few of the many possible embodiments of the invention are illustrated in the accompanying drawings, in which:—

Figure 1 is a side elevation of a safety razor constructed in accordance with the present invention; Fig. 2 is a top plan view thereof; Fig. 3 is a bottom view of the same; Fig. 4 is a section taken on line 4—4 of Fig. 2; Fig. 5 is a sectional view of a detail of construction, on a larger scale; Fig. 6 is a section similar to the one shown in Fig. 4 showing a strop in operative relation thereto; and Fig. 7 is a section taken through a modified detail of construction.

Referring now first to Figs. 1 to 6, inclusive, of the drawings, the numeral 10 indicates a base frame, from which rise two bearing plates 11, in which is rotatably mounted a shaft 12, to the latter being fixed a blade holder 13. This blade holder comprises, in the case illustrated, a piece of metal folded

around the said shaft and secured thereto and forming a pair of jaws 14, adapted to receive a blade 15 between them. Below the shaft 12 is rotatably mounted in the bearing plates 11 a spindle 16, to which is fixed a 55 strop engaging roller 17. This roller is spaced from the blade holder, as more clearly appears from Figs. 4 and 6 of the drawings. Below and in front of the spindle 16 is mounted in the bearing plates a spindle 18, 60 and on the latter is revolvably arranged a strop engaging roller 19. In the plane of the roller 19 is rotatably mounted, in a manner hereinafter to be described, between the bearing plates a third strop engaging roller, denoted by the numeral 20. On one end of the shaft 12 is mounted a pinion 21, meshing with a pinion 22 on the spindle 16. The razor strop 23 is adapted to be engaged with the rollers 17, 19 and 20, and, due to the connection above referred to between the shaft 12 and spindle 16, the movement of the roller 17, when engaged with a strop, is imparted to the shaft 12 to swing the blade holder 13 and the blade 15 back and forth, thus engaging first one side and then the other side of the blade with the strop, attention being called to the fact that the roller 17 and the rollers 19 and 20 frictionally engage 70 opposite sides of the strop, as well known 80 in constructions of this type. Therefore, when the razor frame is reciprocated back and forth in relation to the strop, the frictional engagement of the strop with the roller 17 revolves the latter first in one direction and then in the other.

The frame 10 is, preferably, detachably mounted upon a handle 24.

With the blade co-operates a blade support 25 which is, preferably, made of wire 90 bent into bail-shape. The length of this support exceeds somewhat that of the length of the blade, and it includes a bar 26, extending in parallel relation to the cutting edge 27 of the blade, and two rearwardly extending sections 28 which extend at right angles to the said bar, the free ends of the said rearwardly extending sections being bent toward one another, as indicated at 29, and are each extended through an aperture 30 in the respec- 95 100

tive bearing plate 11 into the hollow roller 20 above referred to. In Fig. 5 of the drawings the inwardly bent sections 29 of the blade holder are shown as being reduced in 5 diameter, but this is not essential. As appears from the foregoing the blade holder is pivotally mounted on the bearing plates 11, its sections 28 being spaced from the outer faces of the said bearing plates and adapted 10 to co-operate with rivet heads 31 on the ends of the spindle 18. These rivet heads extend beyond the outer faces of the said bearing plates and co-operate with the blade holder in a manner hereinafter to be described.

15 On the bar 26 is rigidly mounted a pair of lugs 32, spaced apart a distance that is somewhat less than the length of the razor blade. These lugs may be of any suitable construction, comprising, in the case illustrated in 20 Figs. 1 to 6, inclusive, of the drawings, each an upwardly and rearwardly extending portion 33, which is adapted to overlie one end of the cutting edge of the blade, and an upwardly extending portion 34, disposed in 25 rear of the bar 26 and adapted to abut against the underface of the blade. When the blade is in engagement with these lugs, it is held in shaving position upon the blade support, its cutting edge being disposed in 30 rear of the front edge 35 of the bar 26 and spaced from the said bar a distance necessary to obtain proper shaving. The bar forms thus a guard for the cutting edge of the blade. As appears from Figs. 1 to 6, in 35 clusive, of the drawings, the lugs 32 partly embrace the bar 26, projecting in front thereof. This, however, is not essential. It is possible to so construct the said lugs that they are wholly disposed in rear of the front 40 edge of the said bar, as clearly shown at 36 in Fig. 7 of the drawings. In this instance the lugs are also each provided with an upwardly and rearwardly extending portion 37, for engagement with the cutting edge of 45 the blade, and with a portion 38 adapted to abut against the underface of the blade.

In the positions of the elements shown in 50 Figs. 1 to 4, inclusive, of the drawings, the blade support and the guard, forming part thereof, are in shaving positions. If it is intended to strop the razor, the said blade support is swung from the position shown in Fig. 1 of the drawings, into the position shown in Fig. 6 of the drawings, the blade 55 being thus disengaged from the positioning lugs 32, thereby permitting the said blade to be swung into a position in which it may be stropped. After the stropping operation, the strop 23 is disengaged from the razor 60 and the blade support swung from the position shown in Fig. 6 of the drawings into that shown in Figs. 1 to 4, inclusive. As it is swung into the said position, the rivet 65 heads cause first a longitudinal expansion, as it were, of the blade support, when the

latter is being engaged with the rivet heads, and, when the sections 28 of the support have passed the highest points of the rivet heads the support is kept firmly in shaving position. Of course, any other suitable construction may be employed for this purpose without departing from the invention, which lies mainly in the provision of a bail-shaped blade support, pivotally mounted on the bearing plates of the device and provided with lugs, which each have a cutting edge overlying portion and a razor blade underface engaging section.

The advantages of the construction herein described are not only simplicity, ease of manufacture, lightness in weight, but consist also in that the underface of the front portion of the blade is free, so that not only will lather drop off the razor during shaving, but the razor may also be conveniently rinsed under a faucet for cleaning purposes. It is to be noted that a considerable amount of material is saved in the construction herein described compared with the devices heretofore in use, in which the combined blade support and guard is usually in the form of a solid curved plate provided with guard teeth. In the case illustrated the guard of the razor is in the form of a smooth bar, which not only can be conveniently cleaned but presents a smooth surface to the skin as the razor is being drawn over the face of the user. If found necessary, transverse grooves may be cut into the upper face of the guard bar to obtain the effect of the usual guard teeth.

What I claim is:—

1. A safety razor comprising a frame including two spaced bearing plates, a blade holder oscillatably carried on said plates, a blade on said holder, a bail-shaped support including a bar element for co-operation with the cutting edge of said blade and two rearwardly extending sections extending in parallel relation to and spaced from the outer faces of said bearing plates, the free ends of said rearwardly extending sections extending through said bearing plates toward one another and forming pivot pins for said blade support, means on said bar element adapted to support said blade and for spacing its cutting edge from said bar element, and a strop engaging roller rotatably arranged on the free ends of said pivot pin elements.

2. A safety razor comprising a frame, including two spaced bearing plates, a blade holder oscillatably carried by said plates, a blade on said holder, a blade support made of a single piece of wire bent into bail-shape and including a bar extending in parallel relation to the cutting edge of said blade and two rearwardly extending sections running at right-angles to said bar and having their free ends bent toward one another, said bearing plates being provided with two registering apertures in which the free ends of said

bail-shaped wire are seated whereby said support is pivotally mounted on said frame, means on said bar adapted for supporting said blade and for spacing its cutting edge from said bar, two projections on the outer faces of said bearing plates for co-operation with the two rearwardly extending sections of said blade support, said projections causing said rearwardly extending sections to recede from one another when riding over the same and permitting the same to spring back to normal positions when disengaged from said projections so that said blade support is kept by said projections in shaving positions when said lugs are in engagement with said blade.

Signed at New York, in the county of New York, and State of New York, this 21st day of March, A. D. 1928.

JOSEPH MUROS.
